UNITED STATES PATENT OFFICE.

SAMUEL SILVERMAN, OF NEWARK, NEW JERSEY, ASSIGNOR TO THE RAUCHBACH-GOLDSMITH CO., A CORPORATION OF NEW JERSEY.

DRAWER-LOCKING MECHANISM FOR WARDROBE TRUNKS.

Application filed February 16, 1926. Serial No. 88,538.

This invention relates, generally, to improvements in wardrobe trunks; and the invention has reference, more particularly, to an improved means for simultaneously locking a plurality of drawers with which one of the trunk sections is ordinarily provided.

The invention has for its principal object to provide a strong, durable and easily manipulated locking means to serve all the drawers in the drawer section of a wardrobe trunk, and which is of such character that the same may be quickly and easily moved to either locked or released relation to the drawers by one operation.

The invention has for a further object to provide a novel drawer locking means adapted to provide a two-point engagement with each drawer, whereby the drawers are secured at points adjacent to each side thereof, thus firmly retaining the same, and avoiding both undue play and undue stresses and strains on the drawer bodies.

Other objects of this invention, not at this time more particularly enumerated, will be clearly understood from the following detailed description of the same.

With the various objects of this invention in view, the same consists, primarily, in the novel drawer locking means hereinafter set forth; and, the invention consists, furthermore, in the novel arrangements and combinations of the various devices and parts, as well as in the details of the construction of the same, all of which will be more fully described in the following specification, and then finally embodied in the appended claims.

The invention is clearly illustrated in the accompanying drawings, in which:—

Figure 1 is a perspective view of a wardrobe trunk, opened to show the drawer section, the latter section being partly broken away to show the location of the novel drawer locking means made according to and embodying the principles of this invention; Figure 2 is a transverse vertical section taken through the drawer section of the trunk, showing the locked position of the drawer locking means; Figure 3 is a similar view, showing the released position of said drawer locking means; Figure 4 is a fragmentary perspective, somewhat enlarged, and showing the means for manipulating the drawer locking elements; and Figure 5 is a

perspective of a drawer member showing the locking bar receiving sockets thereof and portions of the locking bars which cooperate therewith.

Similar characters of reference are employed in all of the hereinabove described views, to indicate corresponding parts.

Referring now to said drawings, the reference character 6 indicates the drawer containing section of a wardrobe trunk, provided on its interior sides with suitably disposed supporting slideways 7, upon which the several drawers 8 are movably carried in the usual manner. Connected with the rear wall 8' of each drawer, adjacent to each side of the latter, are socket brackets 9, having rearwardly off-set inwardly directed lock tongues 10, which are parallel to but spaced away from the rear wall 8' so as to provide receiving sockets adapted to admit the locking bar elements, to be subsequently described, beneath said lock tongues 10.

Pivotedly mounted on a fulcrum stud 11 which is fixed to the rear wall 6' of the trunk section 6 adjacent to the top end thereof, and intermediate the sides thereof, is a rotatable lever 12 having oppositely directed free end portions 13 and 13'. A similar rotatable lever 14 having oppositely directed free end portions 15 and 15' is mounted on a fulcrum stud 16 adjacent to the lower end of said trunk section 6, and in vertical alignment with said upper fulcrum stud 11.

Pivotedly interconnecting corresponding ends of said levers 12 and 14, as e. g. the respective ends 13 and 15 thereof, is a vertical transmission bar 17, the same having an extension 18 at its upper end.

Supported for rotation in bearings 19 connected with the upper end wall of said trunk section 6 is a shaft 20, which extends inwardly from the front side of said trunk section 6 toward the rear wall thereof. Connected with the inner end of said shaft 20 is a crank-arm 21, the free end of which is pivotally coupled with the extension 18 of said transmission bar 17. Connected with the outer end of said shaft 20 is a lever arm 22. Hingedly secured to said lever arm 22 is a lock-hasp 23, which can be turned down, when the shaft 20 is rotated to bring the drawer locking mechanism into locked position, so as to interlock with the front of the upper drawer through the medium

of any suitable key-controlled lock-mechanism 23'.

The reference characters 24 and 24' indicate vertically disposed locking bars which are laterally movable in guide yokes 25, the latter being fastened in desired locations upon the interior of said rear wall 6' of the trunk section 6. Interconnected between the free end portion 13 of the rotatable lever 12 and the upper end of the locking bar 24 is a link 26, and in like manner, interconnected between the free end portion 15 of the rotatable lever 14 and the lower end of said locking bar 24 is a similar link 27. Interconnected between the free end portion 13' of the rotatable lever 12 and the upper end of the locking bar 24' is a link 26', and in like manner, interconnected between the free end portion 15' of the rotatable lever 14 and the lower end of said locking bar 24' is a link 27'.

When the drawers 8 are inwardly thrust to closed position within the trunk section 6, and the drawer locking mechanism is disposed in locked relation thereto, said locking bars 24 and 24' will be respectively entered beneath the lock tongues 10 of the socket brackets 9 at the respective sides of the rear end of each drawer, thus retaining said drawers 8 against outward movement. When the locking mechanism is thus disposed in locked relation to the drawers, the lock-hasp 23 is swung down into interlocked relation to the lock-mechanism 23' of the top-drawer, as shown in Figure 1. When thus disposed and conditioned, the drawer locking mechanism is secured against surreptitious or unauthorized manipulation, so that only the possessor of a proper key may release the same for manipulation.

The possessor of a proper key, when desirous of unlocking the drawers 8, inserts the said key in the hasp lock device and unlocks the same so that the lock-hasp 23 may be disengaged from the top drawer. The lock-hasp being free, the operator thereupon turns or swings upward the lever arm 22, thereby rotating the shaft 20 to transmit a downward swinging movement to the crank arm 21 connected with the inner end of said shaft 20. The downward swinging movement of said crank-arm 21 produces a downward longitudinal movement of said transmission bar 17, which by reason of its pivotal connection with the respective rotatable levers 12 and 14, causes the same to turn on their fulcrums from a substantially normal horizontal position, to a substantially vertical position. The turning movement of said levers 12 and 14 swings downwardly the respective free end portions 13 and 15 thereof, and upwardly the respective free end portions 13' and 15' thereof. This movement operates to draw inwardly and laterally toward each other, the respective locking bars 24 and 24', the

movement being transmitted to said respective locking bars by the links 26 and 27 and 26' and 27'. The inward lateral movement of said locking bars 24 and 24' withdraws the same from beneath the lock tongues of the socket brackets 9 connected with the rear of each drawer, and consequently frees said drawers from the restraint of said locking bars, so that the drawers may be selectively opened at the will of the operator, all as will be understood from an inspection of Figures 2 and 5 more particularly. It will be understood, that a reversal of the above described operations will, after the drawers 8 are closed, reengage the locking bars 24 and 24' with the lock tongues 10 of the socket brackets 9, whereby said drawers are all simultaneously returned to locked condition.

From the above description it will be evident that I have provided a relatively simple, and yet very effective drawer locking mechanism for wardrobe trunks, which operates to securely retain the drawers in locked position, with a minimum of strain upon the drawer bodies per se, since each drawer is subject to a two-point engagement of the locking mechanism therewith.

Having thus described my invention, I claim:

1. The combination with the drawer section of a wardrobe trunk provided with a plurality of vertically aligned slidable drawers, each drawer having socket brackets at its rearward end adjacent to each side thereof, of a locking mechanism movable into and out of engagement with said socket brackets, said locking mechanism comprising vertically spaced rotatable levers fulcrumed on the interior of the rear wall of said drawer section, said rotatable levers having oppositely projecting free end portions, a vertical transmission bar pivotally connected with and between corresponding free end portions of said rotatable levers, laterally movable locking bars respectively positioned to engage the drawer socket brackets at opposite sides of said drawers, links interconnecting corresponding free end portions of said rotatable levers with the upper and lower ends of said respective locking bars, a rotatable shaft mounted at the top of said drawer section, said shaft having at its inner end a crank arm connected with the upper end of said transmission bar, and a lever arm on the exterior end of said shaft for manipulating the same.

2. A locking mechanism for the drawer section of wardrobe trunks, comprising vertically spaced rotatable levers fulcrumed on the interior of the rear wall of said drawer section, said rotatable levers having oppositely projecting free end portions, a vertical transmission bar pivotally connected with and between corresponding free end portions

of said rotatable levers, laterally movable locking bars respectively positioned to engage means at opposite sides of the drawers of said drawer section, links interconnecting 5 corresponding free end portions of said rotatable levers with the upper and lower ends of said respective locking bars, a rotatable shaft mounted at the top of said drawer section, said shaft having at its inner end a 10 crank arm connected with the upper end of said transmission bar, a lever arm on the exterior end of said shaft for rotating the

same, a lock-hasp hinged to said lever arm, and key lock mechanism connected with the uppermost drawer with which said lock-hasp may be interlocked when said lever arm is positioned to move the drawer locking mechanism to locked engagement with said drawers. 15

In testimony, that I claim the invention set 20 forth above I have hereunto set my hand this 26 day of December, 1925.

SAMUEL SILVERMAN.
